UNITED STATES PATENT OFFICE.

CHARLES H. HAESLER, OF PHILADELPHIA, PENNSYLVANIA.

AIR-COOLED PNEUMATIC HAMMER.

Application filed October 23, 1920. Serial No. 419,018.

In the art of driving rivets it is customary to heat them in order to facilitate their driving or upsetting. It is now customary to drive the rivets by means of pneumatic hammers. When a pneumatic hammer is employed to continuously drive hot rivets, the rivet set, die or other working tool which is carried at the front end of the cylinder of the hammer becomes heated from contact with the hot rivets. This heat is in part communicated from the shank of the rivet set to the front end of the cylinder and such heating of the front end of the cylinder gradually increases. If this heating action increases to such an extent as to cause the cylinder to expand at its front portion, the bore of the cylinder will be contracted and the piston will stick.

In the operation of manually supported pneumatic hammers in driving hot rivets it is necessary in order to properly manipulate the tool that the operator hold the front end of the cylinder with one hand and the heating of the front part of the cylinder under rapid continuous work becomes so great as to burn the operator's hands and renders it necessary for the operator to employ an insulating glove and in some cases the heat is unbearable to the hand.

In pneumatic riveting hammers of the portable type adapted for manual manipulation, it is customary to have the main exhaust of compressed air from the cylinder pass direct to the atmosphere at the rear end of the cylinder or to lead such exhaust to the atmosphere through ports and passages in the cylinder and the sleeve portion of the handle at the rear end of the cylinder. In riveting hammers constructed in this manner the compressed air at its point of exhaust to the atmosphere expands and causes a decided drop in its temperature and in some instances, for example, in cold weather, when the hammer is operated on outside construction work, the exhaust passages at their outlet from the cylinder freeze or tend to freeze thereby causing a choking and irregular action of the hammer piston and a loss of power and in some cases a complete stoppage of the piston movement.

To overcome the above objectionable results in the operation of pneumatic hammers and with other objects in view which will hereinafter more fully appear, my invention comprehends in its broad and generic scope a novel construction and arrangement of an

air cooled pneumatic hammer wherein one is enabled to utilize and so direct the blast of cool air exhausted from the cylinder as to prevent the front end of the cylinder becoming heated to a degree unbearable to the hand of the operator or to cause irregular action or stoppage of the reciprocating piston.

It further comprehends a novel construction of a hammer cylinder having means to direct the exhaust air to the forward end of the cylinder.

It further comprehends a novel construction of a cylinder which is provided with radiating portions or ribs preferably extending longitudinally of the cylinder and subjected if so desired to the cooling action of the exhaust air.

It further comprehends a novel construction of a cylinder having a novel arrangement of exhaust ports therein and a novel construction and arrangement of a sleeve which causes the air to exhaust at a desired place in proximity to the forward end of the cylinder.

Other novel features of construction and advantage will hereinafter appear in the detailed description.

For the purpose of illustrating my invention, I have shown in the accompanying drawings embodiments thereof which are at present preferred by me, since these embodiments will be found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in longitudinal section, a pneumatic hammer, embodying my invention.

Figure 2 represents a section on line 2—2 of Figure 1.

Figure 3 represents, in longitudinal section, another embodiment of my invention.

Figure 4 represents a section on line 4—4 of Figure 3.

Figure 5 represents an end elevation of the split sleeve.

Similar numerals of reference indicate corresponding parts.

Referring to the drawings.

1 designates the handle of a pneumatic

hammer embodying my invention. The handle is provided with a grasping portion 2 and with a sleeve 3 which is recessed to form a tapered socket 4 which extends through-
 5 out the greater part of the sleeve. 5 designates a cylinder or barrel, the inner end of which is provided with a tapered portion 6 which is machined to fit the corresponding tapered socket 4 in the handle. The cylinder 5 is provided with a piston chamber 7 in which reciprocates a piston 9 having in the form illustrated a reduced extension or impact portion 10 at its forward end, such portion being adapted to impact against the
 10 shank of a working tool 11. The grasping portion 2 of the handle contains a manually controlled throttle valve mechanism 12 which controls the passage of motive fluid from the inlet 13 to the passage 14 which communi-
 15 cates with the chamber 15 of the main distribution valve 16. The chamber 15 communi-
 20 cates by means of ports 17 with the valve chamber 18 in which is mounted a valve 19. The valve chamber 18 communi-
 25 cates by means of a passage 20 with the rear end of the piston chamber 7 and by means of a passage 21 with one or more passages 22 in free communication with the forward end of the piston chamber 7.
 30 23 designates exhaust ports which, as shown in Figures 1 and 2, communicate with the piston chamber 7 intermediate its ends and with exhaust passages 24 which communicate with the atmosphere by means of the
 35 exhaust ports 25, it being seen from Figure 2 that I employ a number of these exhaust ports, eight of them being shown in Figure 2, so that the exhaust air is distributed substantially around the forward end of the
 40 cylinder 5.

In the embodiments seen in Figures 3, 4 and 5, the ports are formed in a similar manner to that seen in Figure 1, it being seen that the cylinder has formed in its outer periphery the slots 26 which communicate with the ports 23 and which discharge to the atmosphere through the ports 27. 28 designates a split sleeve which has a clamping or other fit on the cylinder 5 which is turned down, as indicated at 29, to form the shoulders 30 and 31 against which the ends of the split sleeve 28 abut. It will be seen that in this embodiment the cylinder 5 can be turned down intermediate its ends to
 45 form a reduced diameter to receive the tem-
 50 pered split sleeve 28 which can be expanded and driven into position and when in position will contract and have its outer diameter flush with the outer diameter of the cylinder 5.
 55

In the operation of the pneumatic hammer it will be understood to those skilled in the art that upon the manual manipulation of the throttle valve mechanism to move its throttle valve into open position, the live

motive fluid entering the inlet 13 passes through the passage 14 to the chamber 15 and thence into the valve chamber 14 and if the valve 19 is in the position seen in Figure 1, the live motive fluid will pass through the 70 passage 20 into the rear end of the piston chamber 7 to effect the forward movement or working stroke of the hammering piston 9.

As soon as the rear end of the piston 9 75 passes the ports 23, the live motive fluid in rear of the piston can pass to the atmosphere through the exhaust ports 23, exhaust passages 24 and exhaust ports 25 which are disposed around the forward end of the 80 cylinder so that the exhaust air will have a cooling action on the cylinder and its temperature will be prevented from increasing to an objectionable degree.

When the valve 19 is in a position re-
 85 versed to that seen in Figure 1, the live
 90 motive fluid can pass through the passage
 21, passage 22 into the forward end of the
 95 piston chamber and acting against the for-
 ward end of the piston will cause the piston
 to move rearwardly. As soon as the shoul-
 100 der in proximity to the forward end of the
 piston uncovers the ports 23, the motive fluid
 is free to exhaust to the atmosphere through
 such ports 23, passage 24 and ports 25.

The valve 19 is shifted from one position to another as the pressure of live motive fluid on one side of the piston is decreased by the exhaust action thus causing a drop in pressure on one side or the other of the 100 valve.

It will be apparent from the foregoing that in accordance with my present invention, I provide means for discharging the 105 exhaust air through and around the forward end of the hammer cylinder so that the forward end of the cylinder will be maintained at all times under working conditions in such condition that it can be readily grasped and manipulated by the operator.

It is of course to be understood that my present invention is not limited to any special type of pneumatic hammer but can be employed to advantage with any desired or conventional type of main distribution valve mechanism, throttle valve mechanism or hammering piston, the invention residing more particularly in the construction of the barrel or cylinder.

The flutes or grooves contributing to form the walls of the exhaust passages are preferably about evenly distributed around the circumference of the cylinder and form a series of heat absorbing and heat radiating portions or ribs which aid in dissipating the 115 heating that may occur during the operation of the pneumatic tool.

I have found in practice that very ad-
 120 vantageous results are obtained by so con-
 125 structing the cylinder that heat radiating 130

and absorbing portions are formed which preferably but not necessarily extend in a direction longitudinally of the cylinder. It is desirable but not essential to have the exhaust of motive fluid directed towards or into the passages which the walls of the heat radiating portions contribute to form.

In accordance with my present invention, I am enabled to overcome the excessive heating of the cylinder of the pneumatic hammer so that the pneumatic hammer can be readily manipulated by the operator.

It will now be apparent that I have devised a new and useful construction of an air cooled pneumatic hammer which embodies the features of advantage enumerated as desirable in the statement of the invention and the above description, and while I have, in the present instance, shown and described preferred embodiments thereof which will give in practice satisfactory and reliable results, it is to be understood that such embodiments are susceptible of modification in various particulars without departing from the spirit or scope of the invention or sacrificing any of its advantages.

Having thus described my invention, what I claim as new and desire to secure by Letters Patent, is:

- 30 1. In a pneumatic hammer, a cylinder having a piston chamber, a piston in said chamber, means to control motive fluid to effect the reciprocations of said piston, said cylinder being provided with a plurality of longitudinally extending exhaust grooves distributed around its circumference to form a series of heat radiating surfaces, and separate means surrounding the cylinder to cover the major portions of said grooves.
- 40 2. A pneumatic hammer having a cylinder provided with exhaust ports opening into its piston chamber intermediate its ends and having longitudinally extending exhaust grooves in its periphery communicating with said ports, and a sleeve surrounding said cylinder to cover said grooves and

contributing with the cylinder to form exhaust passages discharging to the atmosphere near the forward end of the cylinder.

3. A pneumatic hammer, comprising a cylinder having a piston chamber, a piston for the piston chamber, means to introduce live motive fluid into opposite ends of said piston chamber to effect the reciprocatory movements of said piston, exhaust ports opening into the piston chamber at its rear portion and uncovered by the piston prior to its reaching the end of its rearward stroke, and longitudinally extending exhaust passages within the wall of said cylinder communicating with said ports, located at substantially equal intervals around the circumference of the cylinder to cool it and discharging through the outer periphery of the cylinder near the forward end of the piston chamber.

4. A pneumatic air hammer comprising a cylinder having a main air chamber and means for supplying air under pressure to the ends of said main air chamber, a piston in said main air chamber, said cylinder being provided at points spaced about the air chamber with a plurality of longitudinally extending grooves having their rear ends formed with radial branches communicating with said chamber, and a longitudinally split sleeve surrounding the intermediate portion of said cylinder and covering the major portions of said grooves.

5. In a pneumatic hammer, a cylinder having a piston chamber, a reciprocating piston, a valve controlling admission of fluid to said piston chamber, exhaust ports opening into the piston chamber at its rear portion and exhaust passages extending forwardly from said ports in the wall of said cylinder and spaced around its circumference to cool it, said exhaust passages being of greater length than the length of said piston and discharging freely to the atmosphere.

CHARLES H. HAESELER.
